US0D1001200S

(12) **United States Design Patent** (10) **Patent No.:** **US D1,001,200 S**
Liu (45) **Date of Patent:** **** Oct. 10, 2023**

(54) **SCOOTER**

(71) Applicant: **Pinheng Core Energy Technology (Shenzhen) Co., Ltd.**, Shenzhen (CN)
(72) Inventor: **Liguang Liu**, Dianbai (CN)
(73) Assignee: **Pinheng Core Energy Technology (Shenzhen) Co., Ltd.**

(**) Term: **15 Years**

(21) Appl. No.: **29/887,006**

(22) Filed: **Mar. 16, 2023**

(51) LOC (14) Cl. **12-11**
(52) U.S. Cl. **USPC D21/423; D12/423**

(58) **Field of Classification Search**
USPC D21/423, 419, 421, 432; D12/8, 107,

(57) **CLAIM**

The ornamental design for a scooter, as shown and described.

DESCRIPTION

FIG. 1 is a first perspective view of a scooter showing my new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof; and,

FIG. 8 is a bottom view thereof.

1 Claim, 8 Drawing Sheets
